UNITED STATES PATENT OFFICE

WILLIAM G. WALLENBECK, OF CHICAGO, ILLINOIS

HOLDER FOR SAFETY RAZOR BLADES

Application filed February 15, 1930. Serial No. 428,551.

My invention relates to an improved construction of holder for safety razor blades, by which the blades may be securely held for honing and stropping purposes.

5 By my invention I provide a holder for safety razor blades for the purposes referred to, which is very simple in construction, cheap to manufacture and assemble and effective in use. An improved feature of my construction consists in providing the clamping members of the holder with a pivotal support constructed entirely by punch press operations and without the use of a pivot rod, and a further purpose of my invention is to make 10 use of a tubular handle having a readily removable inner frame which affords rigid support for the blade clamping members when in their blade holding position, this construction also affording the utmost of simplicity 15 in assembling the device.

My invention will best be understood by reference to the accompanying drawing showing a preferred embodiment thereof, in which

20 Fig. 1 shows my device in side elevation with a razor blade held thereby,

Fig. 2 is an end view of the parts shown in Fig. 1,

Fig. 3 is a sectional view to an enlarged 25 scale, of the parts shown in Figs. 1 and 2 taken along the line 3—3,

Fig. 4 is a view of the inner frame of the device removed from the handle and in unrestrained condition,

30 Fig. 5 shows in a view similar to Fig. 1 to an enlarged scale, one of the clamping members removed from the rest of the device,

Fig. 6 shows in top view the handle of the device with all of the parts removed therefrom, and

Fig. 7 shows in a view similar to Fig. 3, a modified pivot construction for the blade clamping members.

Similar numerals refer to similar parts 45 throughout the several views.

As shown in Figs. 1 and 2, my device consists of a tubular handle 10, which may, if desired, be formed from sheet metal, and when so formed, the joint between the edges 50 of the blank is preferably in line with the

parts projecting from the handle. The handle 10 contains a frame 11 which is a sliding fit in the handle, and the frame 11 has pivoted thereto at 12, 12 two clamping plates 13, 13 between which the razor blade 14 to be 55 sharpened, may be held.

As shown in Figs. 3 and 4 to an enlarged scale, the frame 11 consists of a strip of spring material bent at its mid portion as indicated at 11a so that the two parts of the frame extend in substantially parallel relation to each other when the frame is inserted in the handle 10. The ends 11b of the frame have formed from them projections 11c, extending towards each other, which are 60 formed from the material of the frame by suitable tools, preferably in a punch press in connection with making the frame. The projections 11c enter apertures 13a in the clamping plates 13 so that when the device 65 is assembled, the plates 13 may be swung pivotally on the projections, outwardly from the handle to permit inserting and removing the razor blades between and from the clamping plates 13 so that when the device 70 is assembled, the plates 13 may be swung pivotally on the projections, outwardly from the handle to permit inserting and removing the razor blades between and from the clamping plates, as desired. Adjacent the portion 75 11a of the frame, its substantially parallel portions are separated a distance equal substantially to the combined thickness of the two plates 13, as a result of which, when the plates are swung to their clamping position 80 indicated in Fig. 1, the inner edges of the plates rest between these portions of the frame, which hold the blades rigidly against lateral movement in the handle 10. The frame 11 is of strip material of such a width 85 that when it is inserted in the tubular handle 10, with the plates 13 between the walls of the frame, movement of the frame in the handle is prevented in all directions excepting longitudinally of the handle, and thus a rigid support is afforded the plates 13 and the razor blade 14 clamped between them, against the pressures exerted upon the blade and plates during honing and stropping operations. 95

As shown in Fig. 6, the handle 10 is provided at one end, and preferably in line with the joint 10a between the edges of the sheet material forming the handle, assuming that it is made from a flat sheet metal blank, 100

with a slot 10b or substantially the length of the plates 13 and of a width substantially equal to the combined thickness of the two plates 13, so that swinging the two plates into the handle with a razor blade 14 between them, brings the edges of the slot 10b snugly into engagement with the plates. This, combined with the action of the frame 11, positively supports the razor blade for the purposes described.

In constructing and assembling the device, the handle 10 is made as described, the plates 13 are blanked and formed as shown in Fig. 5, with pivot apertures 13a in them, the frame 11 is constructed as shown in Fig. 4, the two plates are placed together with their pivot apertures 13a in line with each other and with the projections 11c between which the plates are located, the end portions 11b of the frame 11 are held together by the thumb and finger, with the projections 11c in the apertures 13a, and the frame and plates are pushed into the handle 10 so that the plates will rest in the slot 10b. I find that the spring tension required to be exerted by the frame 11 on the parts for the purposes described, is no greater than can readily be overcome by the pressure of the thumb and finger in assembling the device, and that the resultant friction of the frame 11 in the handle 10 may readily be overcome manually in slipping the frame into the handle with the plates 13 between the end portions of the frame. When the device is assembled as described, the spring tension on the pivot portions of the frame holds the plates in any position to which they may be moved and also holds the pivot projections 11c in the pivot apertures 13a.

In Fig. 7 I show a modified construction in which the clamping plates 13b have pivotal projections 13c formed outwardly from them, preferably by suitable tools during the punching and forming of the plates, and the frame 11d has pivot apertures 11e through its ends in line with and to receive the projection 13c, the resulting pivotal construction being similar to that shown and described in connection with Figs. 3 and 4. In all other respects, the plates 13b and the frame 11d may be of the same construction and have the same manner of assembly in the handle 10, and secure the same results as the plates 13 and frame 11 respectively, the handle 10 being the same in either case.

In this manner I not only afford a positive support for the plates and razor blades, but I also provide a construction by which after the several parts are formed by means of simple punch press operations, no further machine operations of any kind are required in pivotally mounting the clamping plates in the handle, and furthermore the expense of assembling the device is much less than where a further operation or operations are

required in providing a separate pivot pin for the clamping plates, and with the marked advantage that the frame 11 which facilitates the assembling of the device, also affords a much more positive and rigid support for the clamping plates and the razor blades, than is possible where a separate pivot pin construction is relied upon to hold the plates and blades against movement under the pressures exerted upon the blade during stropping or honing.

While I have shown my invention in the particular embodiment above described, it will be understood that I do not limit myself to this exact construction as I may employ equivalents known to the art at the time of the filing of this application without departing from the scope of the appended claims.

What I claim is:

1. In a holder for safety razor blades, the combination of a metal tube comprising integral handle and blade mounting portions, said blade mounting portions having a longitudinal slot extending through its wall from one of its ends, a frame comprising a flat metal bar bent at its mid-portion so its end portions extend in the same general direction and wholly contained in said blade mounting portion, a pair of sheet metal clamping plates of a combined thickness substantially equal to the width of said slot and located between the end portions of said frame, and a pivotal connection between the end portions of said frame and said plates, said frame being slidable in said handle with said plates pivotally mounted upon it for assembling purposes, whereby with said frame assembled in said handle said plates may be swung on said pivotal connection into and from said slot as desired.

2. In a holder for safety razor blades, the combination of a metal tube comprising integral handle and blade mounting portions, said blade mounting portions having a longitudinal slot extending through its wall from one of its ends, a frame comprising a flat metal bar bent at its mid-portion so its end portions extend in the same general direction and wholly contained in said blade mounting portion, a pair of sheet metal clamping plates of a combined thickness substantially equal to the width of said slot and located between the end portions of said frame, and a pivotal connection between the end portions of said frame and said plates, said frame being slid-able in said handle with said plates pivotally mounted upon it for assembling purposes, whereby with said frame assembled in said handle said plates may be swung on said pivotal connection into and from said slot as desired, the walls of said frame adjacent its bent portion being spaced substantially the combined thickness of said plates affording said plates lateral support when in their blade clamping position.

3. In a holder for safety razor blades, the combination of a tubular metal handle having a longitudinal slot at one end, a metal frame 5 slidable into said handle and wholly contained therein in assembled relation, and two blade clamping plates pivotally connected at their ends to said frame and movable on said pivotal connections into and from said slot with said frame in said handle, whereby said plates and said frame 10 may be first assembled and then said assembly may be inserted in said handle to complete the assembly of said holder.

4. In a holder for safety razor blades, the combination of a tubular metal handle having a longitudinal slot at one end, a metal frame 15 slidable into said handle, and two clamping plates pivotally connected at their ends to said frame and movable on said pivotal connections into said slot to hold a razor blade, whereby said plates and said frame may be inserted in said handle in assembled relation, said pivotal connections comprising formed 20 projections and apertures carried by said 25 plates and frame for engagement with each other.

5. In a holder for safety razor blades, the combination of a tubular metal handle having a longitudinal slot at one end, a metal frame 20 slidable into said handle and wholly contained therein in assembled relation, and two blade clamping plates pivotally connected at their ends to said frame and movable on said pivotal connections into and 25 from said slot with said frame in said handle, whereby said plates and said frame may be first assembled and then said assembly may be inserted in said handle to complete the assembly of said holder, said frame having 30 spaced walls receiving said plates between them affording lateral support for said plates in their blade holding position.

6. In a holder for safety razor blades, the combination of a tubular metal handle having 35 a longitudinal slot at one end, a metal frame slidable into said handle, and two clamping plates pivotally connected at their ends to said frame and movable on said pivotal connections into said slot to hold a razor 50 blade, whereby said plates and said frame may be inserted in said handle in assembled relation, said pivotal connections comprising formed 55 projections and apertures carried by said plates and frame for engagement with each other, said frame having spaced walls receiving said plates between them affording lateral support for said plates in their blade holding position.

7. In a holder for safety razor blades, the 60 combination of a tubular handle, a frame comprising a bent metal bar insertible into and removable from said handle, clamping plates pivoted to said frame and movable with said frame into and from said handle, 65 and formed projections and apertures carried

by said plates and frame constituting a pivotal connection between said plates and said frame, said frame having end portions for engaging said plates laterally and distended between its end portions to be free 70 from said plates and snugly engage the inner surface of said handle.

In witness whereof, I hereunto subscribe my name this 3rd day of February, A. D. 1929.

WILLIAM G. WALLENBECK.
